United States Patent Office.

WILLIAM H. FORKER, OF MEADVILLE, PENNSYLVANIA.

Letters Patent No. 77,475, dated May 5, 1868.

IMPROVED PAINT-BRUSH.

The Schedule referred to in these Letters Patent and making part of the same.

TO ALL WHOM IT MAY CONCERN:

Be it known that I, WILLIAM H. FORKER, of the city of Meadville, in the county of Crawford, and State of Pennsylvania, have invented a new and improved Mode of Constructing Paint-Brushes; and I do hereby declare that the following is a full and exact description thereof, reference being had to the accompanying drawings, and to the letters of reference marked thereon.

Figure 1 represents all the parts in complete position as when in use, except the bristles.

Figure 2 shows all the parts clef through their centres, the same letters referring to like parts in all the figures.

I construct my brushes as follows: Around the lower end of the wooden handle A, I fit the conical ferrule F, and above this I fix, with a rivet, the screw-ferrule B, on which the nut C works. The cap D is made to slip over the screw B, and is held against the butts of the bristles and upper rim of the band E by the nut C. The band E is made to correspond with the size of the brush required, and supplies the place of twine in ordinary brushes, and can be made of brass, tin, or other metal. When the brush is to be put together, a suitable quantity of bristles is thrust, with their taper ends first, through the band E, and the butts made level with the upper rim of E. Then the cap D is put in place, and the handle A, with the screw B and ferrule F, fixed to it, is pushed up through the middle of the bristles till the conical ferrule wedges the bristles securely between it and the band, when the nut C fastens the whole in one.

The object of the conical ferrule F is to prevent the loosening of the bristles by the shrinkage of the wooden handle.

I do not claim the tightening of the bristles by the action of a conical wedge or nut, when the same is forced either up or down, by turning the screw with the brush-handle, when the said cone is surrounded with bands or staves inside the brush; but

What I do claim as my invention, and desire to secure by Letters Patent, is—

The solid wooden handle A, of full length, with its conical ferrule F, which, in combination with the nut C, operating on the cap D from above, holds all the parts firmly together, when constructed as and for the purpose set forth.
